UNITED STATES PATENT OFFICE.

SAMUEL C. BOWEN, OF MEDINA, NEW YORK.

COMPENSATOR FOR WIRE FENCES.

SPECIFICATION forming part of Letters Patent No. 606,506, dated June 28, 1898.

Application filed June 17, 1896. Serial No. 595,869. (No model.)

To all whom it may concern:

Be it known that I, SAMUEL C. BOWEN, a citizen of the United States, residing at Medina, in the county of Orleans and State of New York, have invented certain new and useful Improvements in Compensators for Wire Fences; and I do hereby declare the following to be a full, clear, and exact description of the invention, such as will enable others skilled in the art to which it appertains to make and use the same.

The invention relates to certain improvements in the construction of wire-fence compensators; and it consists, essentially, of two brackets having a coil-spring interposed between them and each carrying a winding-spindle journaled therein, as will be herein-after more fully explained.

The object of the invention is to principally provide an efficient device in a fence line-wire of a greater capacity for winding the wire from each way than those now used on posts and which will automatically tension the line-wires of a fence so as to compensate for the expansion and contraction of the same.

Another object of the invention is to simplify and cheapen the construction of the compensator without affecting its durability and efficiency in service.

These objects are attained by means of the structure illustrated in the accompanying drawings, in which—

Figure 1 is a side elevation of a portion of a wire fence, showing my improved compensator applied to the line-wires thereof; Fig. 2, a longitudinal section of the compensator somewhat enlarged; Fig. 3, a side elevation of one of the brackets and its winding-spindle, and Fig. 4 a modification of Fig. 2.

Referring specifically to the several figures, the numeral 1 indicates the posts, and 2 the line-wires, of the fence. Each line-wire is divided into two sections with the ends overlapping each other, so as to be connected to the opposite ends of an interposed compensating device 3, which consists of two brackets 4 and 5, having a coil-spring 6 interposed between them. Each bracket is formed with a tapering hub 7 and half-bearings 8. The hub of one bracket is seated within one end of the coil-spring, while the hub of the

other bracket is seated within the opposite end of said spring, with the ends of the spring resting against the rear side of the respective brackets.

Journalized in the half-bearings of each bracket is a spindle 9, which is provided at one end with a ratchet-head 10 and at the other end with a square portion 11, which is adapted to receive a wrench or other tool, by means of which it may be rotated. Each spindle is provided with hole 12, in which is secured the end of the divided line-wire.

Each bracket on one of its outer sides is provided with a lug or stop 13, which is arranged in position to be engaged by the teeth of the ratchet-head, and thereby prevent backward rotation of the spindle. Each lug or stop is provided with a right-angle projection 14, which extends a short distance over the face of the ratchet-head, so as to hold the spindle in proper operative position in its bearings. By providing the lug or stop with the projection 14 I dispense with the usual flange on the spindle for accomplishing the same purpose, and the advantage to be derived therefrom is an important one, as I am enabled to decrease both the width of the bracket and the length of the spindle, thereby lessening the expense of construction.

In applying the compensator the end of one section of the divided line-wire (as shown in Fig. 1, the right hand) is secured to spindle 4, and the end of the other section (left hand) is secured to the spindle 5. By rotating the spindle of each bracket the coil-spring is compressed and each section of the line-wire is tensioned, and thereafter the expansion and contraction of the line-wires are automatically compensated for.

In the modification shown in Fig. 4 the coil-spring is dispensed with, the two spindle-supporting brackets being placed end to end. The line-wires are attached to the respective spindles in the same manner as heretofore described. This device is especially adaptable at points where the line-wires are spliced. Instead of splicing the wires the device is inserted, thus saving considerable time and trouble occupied in splicing.

Having thus fully described my invention, what I claim, and desire to secure by Letters Patent, is—

1. In a fence-wire-compensating device, the combination of two hollow supporting-brackets, placed end to end, each provided with a ratchet-head spindle journaled across the outer end of the bracket, with its ratchet-head outside thereof, and a lug or detent, formed on the outside of the bracket, adapted to engage the teeth of the ratchet-head, to prevent backward rotation of the spindle, 5 said lug having a projection arranged to retain said spindle in proper operative position, with a divided fence-wire, one end of which passes through one supporting-bracket and is connected to the spindle of the other bracket, while the other end of the wire passes through the other bracket and is connected to the spindle of the first bracket.
2. In a fence-wire-compensating device, the combination of two hollow supporting-brackets, placed end to end, a spiral spring 10 between said brackets, each bracket being 15
- 20

provided with a ratchet-head spindle journaled across the outer end of the bracket, with its ratchet-head outside thereof, and a lug or detent, formed on the outside of the bracket, adapted to engage the teeth of the ratchet-head, to prevent backward rotation of the spindle, said lug having a projection arranged to retain said spindle in proper operative position, said device being so placed 25 in a divided fence-wire, that one end of the wire will pass through one bracket and be secured to the spindle of the other bracket, while the other end of the wire will pass through the other bracket and be secured to 30 the spindle of the first bracket.

In testimony whereof I affix my signature in the presence of two witnesses.

SAMUEL C. BOWEN.
